UNITED STATES PATENT OFFICE.

CHARLES A. SIVON, OF PASADENA, CALIFORNIA.

PIVOT SINK STOOL.

Application filed January 22, 1925. Serial No. 3,965.

My invention is an improved pivotal stool particularly applicable to sinks, cabinets, benches, etc.

Open faced sinks of which I will hereafter refer are those having an open space in the cabinet part, immediately below the porcelain or cast iron sink.

An object of my invention is to provide a stool which may be readily mounted on an open faced sink, a cabinet or bench, and may be used to sit comfortably upon while working.

Another object is to provide a stool which may be readily mounted on a sink, and which will automatically swing out of the way when not in use, or may be entirely removed if desired.

A further object is to provide a stool capable of horizontal and vertical adjustments in mounting.

Other objects are to provide a stool which is simple in construction, inexpensive to manufacture, and highly efficient in operation.

An object is to provide a novel swinging stool which has its post upon which it pivots integral therewith and which reduces to a minimum the strain applied to the screws or other means securing the stool in place.

Other objects, advantages and features of invention may appear from the accompanying drawing, the subjoined detailed description and the appended claims.

In the drawing in which my invention is illustrated.

Figure 1 is a side elevation of my stool, dot and dash lines indicate a position of the stool swung horizontally on its pivot.

Fig. 2 is a sectional view taken on irregular line x^2-x^2 , Fig. 1.

Fig. 3 is a plan view of my stool.

Fig. 4 is a plan view of the upper stool mounting bracket.

Fig. 5 is a sectional view taken on line x^5 , Fig. 4.

Fig. 6 is a sectional view taken on line x^6 , Fig. 4.

Fig. 7 is a plan view of the lower socket.

Fig. 8 is a fragmentary bottom view of the seat mounting.

Fig. 9 is an end view of the seat mounting shown in Fig. 8.

Fig. 10 is a fragmentary sectional view showing the seat frame mounted in slightly modified form of brackets.

My invention comprises a frame 1 sub-

stantially triangular in shape, such triangle is approximately a $30^{\circ}-60^{\circ}$ triangle; and is provided with a tip 2 which is an extension of the base A. Said triangle is arranged so that the tip 2 extends upwardly from the right angle a of the triangular frame 1 and said frame is also provided with a post 3 which is another continuation or extension of the base A and said post 3 depends from the acute angle b of the triangular frame. The frame is preferably formed of one piece either cast, or of rod, cut and bent to shape and welded at their junctures. The rod is preferably round steel rod.

A flat sheet steel plate 4 is formed or secured as by welding at the outer end of the upper reach 4' forming one side of the triangle, or in other words, at the apex bar 60° angle of the triangular frame 1.

This plate has screw holes 5 extending therethrough, so that screws extend into a wooden seat 6 and secure it to the frame. The seat 6 is preferably round in shape and forms a seating area.

The post 3 is journalled in a bearing formed in a base socket 7, which is secured to the base or floor by screws extending through holes in the semi-circular flange 8 thereof.

The tip at the upper end of the frame 1 is mounted in, and extends through, an angular cast L-shaped bracket 9 having holes 10 in its vertical member to accommodate screws which secure it to the wall.

The horizontal member of the angle 9 has a conical hole 11 extending therethrough and in which the tip 2 is journalled. This hole is tapered at its top as shown in Figs. 5 and 6, so that the bracket may be mounted eccentrically at different positions on its support and with relation to the socket 7, so that the tip 2 will not bind in the hole 11 when moved about its axis. By having the hole 11 in which the tip 2 is mounted a greater distance away from the sink or support c , than the bearing in which the post 3 is mounted, the stool will automatically swing away by gravity from its position in use, to a position in alinement with the face of the sink or cabinet.

In actual practice the bracket 9 is mounted about three degrees left or right of the exact vertical line through the socket 7, as shown in Fig. 1, so that the stool will swing by gravity under the sink or cabinet; i. e., the stool will automatically swing completely

away from the face of the cabinet under the usual recess formed therein when not in use. The height of the seat 6 may be adjusted by cutting off a portion of the post 3 and a consequent lowering of the angle 9 on the wall to which it is secured.

In the modified form shown in Fig. 10, the upper bracket 9 is formed of a stamping and from comparatively light material.

10 The socket 7 is also formed of a light material bent upon itself, by stamping, to form a socket similar to the one already described.

If desired the stool may be entirely removed and stored away. This is accom-

15 plished by lifting the frame 1 upwardly until the post 3 is lifted out its bearing in the socket 7, after which the frame is swung slightly to one side of the socket 7 and the tip 2 removed from the bracket 9.

20 The base of the triangular frame 1 is mounted in approximately vertical position and is extended at each end thereof to form the tip 2 and post 3. The hypotenuse D of the triangle serves as a brace for the seat 6.

25 I claim:

1. In a swinging seat structure, the combination with a floor socket, of a wall bracket disposed above the floor socket and includ-

30 ing therein, the wall of the opening being inclined, a supporting rod having its lower

end journaled in said floor socket and its upper end extending upwardly into the opening of said wall bracket, an arm extending laterally from said rod, and a seat 35 on said arm, the length of the supporting rod above the arm being greater than the depth of the floor socket for permitting the rod to be elevated from the socket and removed from the bracket.

40 2. In a swinging seat structure, the combination with a floor socket, of a wall bracket disposed above the floor socket and including a horizontal arm having a vertical opening therein, the wall of the opening being 45 inclined, a supporting rod having its lower end journaled in said floor socket and its upper end extending upwardly into the opening of said wall bracket, an arm extending laterally from said rod, and a seat on 50 said arm, the length of the supporting rod above the arm being greater than the depth of the floor socket for permitting the rod to be elevated from the socket and removed from the bracket, the socket and the bracket 55 being relatively located to position the supporting rod at an inclination to the vertical.

In testimony whereof, I have hereunto set my hand at Los Angeles, California, this 17th day of January 1925.

CHARLES A. SIVON.
